BRACE FOR A CYCLE SADDLE

George W. Worley, Bolivar, Tenn., assignor to Troxel
Manufacturing Company, Moscow, Tenn.

Filed Apr. 7, 1970, Ser. No. 22,308

Term of patent 14 years

Int. Cl. D12—14

U.S. Cl. D90—15

FIG. 1

FIG. 2

FIG. 3

FIG. 4

FIG. 1 is a front elevational view of a brace for a cycle saddle, showing my new design.

FIG. 2 is a side elevational view thereof.

FIG. 3 is a top plan view thereof.

FIG. 4 is a bottom view thereof.

The rear elevational view, not shown, has substantially the same appearance as the front elevational view shown in FIG. 1, and the side not shown has substantially the same appearance as the side shown in FIG. 2.

I claim:

The ornamental design for a brace for a cycle saddle, as shown and described.
